[57] CLAIM

The ornamental design for an athletic glove, as shown and described.

DESCRIPTION

FIG. 1 is a front elevational view of an athletic glove showing my new design;

FIG. 2 is a rear elevational view thereof;

FIG. 3 is a rear elevational view of a embodiment;

FIG. 4 is a bottom plan view of FIGS. 1 and 3;

FIG. 5 is a front elevational view of a third embodiment of the glove shown in FIG. 1;

FIG. 6 is a front elevational view of a fourth embodiment of the glove shown in FIG. 1;

FIG. 7 is a front elevational view of a fifth embodiment of the glove shown in FIG. 1;

FIG. 8 is a bottom plan view of FIGS. 5, 6 and 7;

FIG. 9 is a front elevational view of a sixth embodiment of the glove shown in FIG. 1;

FIG. 10 is a bottom plan view of FIG. 9;

FIG. 11 is a front elevational view of a seventh embodiment of the glove shown in FIG. 1;

FIG. 12 is a bottom plan view of FIG. 11.

FIG. 13 is a rear elevational view of a modified embodiment of FIG. 2.

The broken lines shown throughout the views indicate stitching.
